GRINDING WHEEL

Herbert R. Simonds, Dayton, Ohio, assignor to
 Simonds Worden White Company, Dayton,
 Ohio, a corporation of Ohio

Application February 15, 1939, Serial No. 256,550

2 Claims. (Cl. 51—209)

This invention relates to a grinding wheel and more particularly a grinding wheel having its grinding face on one side or flat surface of the wheel. It is desirable that such a grinding wheel should have a non-continuous grinding face, that is, that different parts of the grinding face should be spaced one from the other, to prevent excessive heating and to provide for the escape of fine material which is separated from the grinding wheel and from the work during the grinding operation.

One object of the invention is to provide a simple efficient method of producing a grinding wheel having a non-continuous lateral grinding face.

A further object of the invention is to provide a grinding wheel having a plurality of grinding elements so arranged and connected one to the other as to provide a strong durable grinding wheel which will be highly efficient in operation.

A further object of the invention is to provide such a grinding wheel having simple and efficient means for rigidly connecting the grinding elements with a backing plate.

Other objects of the invention may appear as the grinding wheel is described in detail.

In the accompanying drawing Fig. 1 is a side elevation, partly broken away, of a grinding wheel embodying my invention; Fig. 2 is a section taken on the line 2—2 of Fig. 1; and Fig. 3 is a similar section of a portion of the grinding wheel showing the same as mounted on the head of the grinding wheel.

In this drawing I have illustrated one embodiment of the invention but it will be understood that this embodiment has been chosen for the purposes of illustration only and that the details of construction may take various forms.

The grinding wheel comprises a plurality of grinding elements 5, preferably arcuate in form and arranged in radially spaced relation one to the other with their grinding faces, or edges, in a common plane transverse to the axis of rotation of the wheel. As here shown, each arcuate grinding element comprises a complete circle, the several elements being of different diameters and being spaced radially one from the other to provide between adjacent elements an annular space 6.

The several grinding elements are rigidly connected one to the other adjacent those edges thereof which are remote from the grinding edges or faces. This is preferably accomplished by mounting the grinding elements on a backing plate 7 which may be of steel or other suitable

material and which preferably is of the same diameter as the outside diameter of the outermost arcuate grinding element. There may be any suitable number of grinding elements and they may be arranged on the backing plate in any suitable manner which will provide the desired non-continuous grinding face and which will permit the wheel to be maintained in balance. As here shown, three circular grinding elements are arranged concentric with relation one to the other and to the axis of the wheel and are of such width as to provide between them the annular space 6.

In order that the grinding elements may be easily but rigidly attached to the backing plate in such a manner as to provide a strong durable wheel at a low cost I prefer that the backing plate shall be of such character that the grinding elements can be molded directly thereon in such a manner as to firmly unite the grinding elements and the backing plate. As is well understood the grinding elements are usually produced by mixing an abrasive substance or grain with a suitable binder to provide a plastic material which can be molded to the desired form and is then baked or otherwise treated to harden the same. In the present construction the recesses are shown as annular, dovetailed grooves 8 formed in the backing plate and each grinding element has at its inner edge a dove-tailed portion 9 fitting tightly within the corresponding dove-tailed groove. In the manufacture of the wheel the backing plate is placed in a suitable circular mold provided with partitions arranged to divide the grinding material into separate elements of the desired character. The plastic grinding material is introduced into the mold and pressed firmly into the dove-tailed recesses in the backing plate, the various spaces in the mold being filled to a common level so that the grinding faces of the several grinding elements will be in a common plane. After the mold has been filled the formed grinding wheel is removed therefrom and baked or otherwise treated to properly harden the grinding elements.

The finished wheel may be mounted for rotation in any suitable manner but, as here shown, it is rigidly secured to the rotating head 10 of a grinding machine, as by means of screws 11.

It will be apparent that in the grinding wheel so produced the several grinding elements are spaced one from the other to provide a non-continuous grinding face and are rigidly secured to the backing plate so that the wheel as a whole, including the grinding elements and the backing

plate, may be readily secured to and removed from the rotating head of the grinding machine. It will be understood that while I prefer to use circular grinding elements these elements may be segmental in form or otherwise arranged to provide the desired surface.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

- 15 1. In a grinding wheel, a disk-like rotatable backing plate having means for rigidly securing the same to a driving element and having a plurality of annular grooves arranged concentric one with the other and with the axis of rotation of said backing plate, said grooves being of a depth less than the thickness of said backing plate and having enlarged inner portions, a plurality of one piece annular grinding elements of bonded abrasive material molded in the 20 respective grooves, extending outwardly there-

from in radially spaced relation one to the other and having on their outer edges annular grinding surfaces spaced radially one from the other.

2. In a grinding wheel, a disk-like rotatable backing plate having means for rigidly securing the same to a driving element and having in one face thereof a plurality of annular grooves arranged about and spaced different distances from the axis of rotation of said backing plate, said grooves being of a depth less than the thickness 10 of said backing plate and having their inner portions enlarged, and a plurality of grinding elements each comprising a body of bonded abrasive material having a relatively narrow inner edge portion thereof molded in one of said grooves and 15 having on opposite sides of said narrow portions inwardly facing shoulders arranged in supporting contact with said backing plate, each grinding element having at its outer edge a continuous 20 grinding surface and the grinding surfaces of the several grinding elements being arranged in a common plane and spaced radially one from the other.
